ISRAEL L. G. RICE, OF CAMBRIDGE, MASSACHUSETTS.

Letters Patent No. 104,887, dated June 28, 1870.

IMPROVEMENT IN MACHINES FOR MAKING COMPOSITION ROOFING.

The Schedule referred to in these Letters Patent and making part of the same.

I, ISRAEL L. G. RICE, of the city of Cambridge, in the county of Middlesex and State of Massachusetts, have invented a certain Improved Machine for Manufacturing Composition Roofing, of which the following is a specification.

Nature and Object of the Invention.

My invention relates to providing a means by which composition roofing may be made cheaper and more expeditiously than is now done; and

It relates particularly to the roofing manufactured under patents granted to Jay J. Wiggin.

In order to better understand the machine, I will give a brief description of the roofing referred to.

This roofing is made of a compound of coal-tar, lime, and clay, boiled and stirred together. This compound, in a liquid state (that is, the coal-tar is melted, and the other ingredients are so thoroughly mixed that the whole compound is in a thick fluid state) is poured upon a long bed covered with fine sand. This bed is usually twenty-five feet long and two feet wide.

A carriage, having a wood roller, upon which is wound a quantity of thick paper, and also having another roller, to be used as a pressure-roller, is used. This carriage is pushed along over the bed, and, as it moves, the paper is drawn under the pressure-roller and on top of the composition. The composition adheres to the paper, and the roofing is made.

My invention consists in furnishing a bed, over which I draw the paper. Placed over this bed I have a receptacle for composition, from which it flows upon the paper and adheres to it. As the paper is drawn along with the melted composition upon the surface, I give it a sprinkling of fine sand on top, by means of a hopper to hold the sand, and a sieve under it. The paper is drawn along, and the surplus sand scraped off by means of a scraper. It is then drawn between two rollers, which press it out even and smooth.

Description of the Accompanying Drawing.

Figure 1 is a perspective view of a machine embodying my invention.

Figure 2 is a sectional view of the reverse side of the drawing, in perspective.

General Description.

A is the frame of the machine.

B is the bed of the machine.

C is the receptacle for the composition.

D is the sand-hopper.

E, the scraper.

F¹ F², the pressure-rollers.

H¹ H², the gears upon the shafts of the rollers.

I, a crank for operating the machine.

J is a cam upon the shaft of the pressure-roller F¹. K is rod, which is struck by the cam, and then thrown back into place by the spring L. Its object is to give a blow to the sieve M, and thus shake out the sand that is in it.

N is a drum, having an endless belt passing over it, O, and also passing over the drum P. The object of this belt is to receive the roofing as it is given out by the machine.

The paper is put upon a roller, R, and passes under the roller S and over the roller T, and then over the bed B into the receptacle C. The composition then comes in contact with it and adheres to it. There are two sliding partitions that form the front and rear of the receptacle. The one in the rear, U¹, is raised just sufficient for the paper to pass under it; the one in front, U², is raised to the height I want the roofing to be in thickness. The paper is then moved along, and, as it passes under the sand-hopper and sieve, it receives a sprinkling of sand. The surplus sand is then scraped off by the scraper. It then passes between the pressure-rollers and out upon the endless belt. This belt is made long enough to carry the material out a sufficient distance for it to become cool. Thus it is found to require five minutes for the composition to become cool enough to roll up in packages.

Now, the rate I propose to make the roofing is twenty-five feet in length a minute. At this rate the roofing would have to be carried out one hundred and twenty-five feet before it became cool.

When it gets to the drum P I draw it between the rollers V¹ V². The surplus sand in the meantime drops into the box W.

I then cut it off in lengths to suit, with the knife X, and roll it up for sale.

To keep the composition at an even degree of temperature, steam-pipes should be put into the receptacle.

If the weight of the composition be too heavy upon the paper, a bottom to the receptacle may be put in above the bed B B, and the compound be allowed to flow out upon the paper by means of an aperture made in the bottom of the receptacle, and being regulated by an adjustable scraper.

If the roofing be too soft to be drawn out by the friction of the pressure-rollers, friction-rollers may be placed out some distance from them, at a point where the roofing is cold, and then these friction-rollers would draw it out, as they are made to revolve by any suitable means.

This machine may be used for manufacturing composition roofing, sidewalks, and, perhaps, by filling the receptacle with glue and keeping it hot, sand-paper and emery-cloth might be made.

If the material should be in such a condition that an additional rolling would improve it, pressure-rollers may be put on the machine, one being placed under the belt and another above it, and the roofing be made to pass between them and be pressed.

Claims.

What I claim as my invention, and desire to secure by Letters Patent, is—

1. The hopper D, sieve M, and scraper E, arranged between the receptacle C and the pressure-rollers F¹ F², substantially as shown and described.

2. The rollers R S T, receptacle C, bed B, hopper D, sieve M, scraper E, and pressure-rollers F¹ F², when combined, substantially as herein shown and described, and for the purpose specified.

3. The combination with the above-named parts, of the drum N, endless belts O, drum P, rollers V¹ V², and knife X, as shown and described.

ISRAEL L. G. RICE.
